RADIATOR.

1,214,654.

Specification of Letters Patent.

Patented Feb. 6, 1917.

Application filed April 21, 1909. Serial No. 491,301.

To all whom it may concern:

Be it known that we, GEORGE DE FÈVRE, a citizen of the Republic of France, and JAMES E. WOODBRIDGE, a citizen of the 5 United States, both residing in the borough of Manhattan, city, county, and State of New York, have invented a new and useful Improvement in Radiators, of which the following is a description.

10 This invention relates to coolers or radiators for internal combustion engines, or to be used in connection with internal combustion engines, automobiles, flying-machines, locomotive engines of all kinds, and for condensing wet-steam at low pressure, and has special reference to the structure of the tubing, the combination of the tube-sections thereof, and also to the process for producing the tubing and the radiator.

20 Among the objects of our invention may be noted the following: To provide a radiator which will be simple in construction, quickly constructed, made of separable parts, quickly and easily repaired, strong, and of long life; to provide a form of honeycomb tubing by means of which a greater radiating surface and free circulation of the water between the tubes are secured; to provide a 25 practical and economical process or mode of constructing the radiator and the tubing thereof; and to provide a sheet-structure which, when sections thereof are put together, will quickly produce the form of tubing desired and facilitate the construction 30 of the radiator.

With the above objects in view, and others which will be detailed during the course of this description, our invention consists in the parts, features, elements, and combinations 40 of elements constituting the radiator or condenser, and the blank for the tubing, and also in the mode of producing the latter and the radiator, all as hereinafter described and claimed.

45 In order that our invention may be clearly understood, the accompanying drawings are provided in which:

Figure 1 represents, in front elevation the radiator embodying our invention; Fig. 2 is a section on the line 2—2 of Fig. 1; Fig. 3 is a perspective view of the blank from which the tubing is made; Fig. 4 is a vertical cross-

section of a group of tubes made according to our invention and showing the separating strips or partitions; Fig. 5 is a cross-section 55 of a group of tubes showing the water-channels and recesses between the tubes; Fig. 6 is a view similar to Fig. 5; Fig. 7 is a vertical section of a tube showing another mode of flaring the end thereof for spacing purposes; Fig. 8 is a longitudinal vertical section, broken in the middle, showing a tube section made of a single piece of sheet material; Fig. 9 is a transverse section of a single tube made of a single piece of material. 60 65

Referring to the drawings, the numeral 1 indicates the frame, which may be made of any suitable outline or design, but shown as rectangular; 2 the cover of the frame; and 3 the base of the frame. Within the body- 70 portion 1, the tubes, generally indicated by 4, may be set either vertically or horizontally, as may be desired, or according to the type of the condenser or radiator to be constructed. 75

The material of which the tubing is formed is preferably thin sheet-copper, though brass and other metals may be employed and, according to our invention, the tubing is made up from sheet material of 80 any suitable width, though ordinarily from two to five inches wide. The sheet material is crimped or folded periodically so as to produce the equi-distant ribs 5, extending transversely thereof and the flat walls, or 85 webs, 6, between said ribs, the crimping operation doubling the material upon itself so as to superpose two portions thereof, but leaving a narrow recess or space 7 between the same so that the inner edges of the ribs 90 will be closed and rounded as at 8, while at the outer edges, or at the juncture thereof with the webs 6, there will be an opening 9. Each rib, at predetermined distances, is 95 tightly compressed so as to produce the comparatively solid portion of the rib 10, the compression closing the space between the superposed portions, as clearly indicated in Fig. 3. This structural feature is produced at predetermined points in each rib, usually 100 at the ends and at one or more intermediate points. The crimped blank is run out in indefinite lengths from the sheet material and then sections cut therefrom transversely be-

between the ribs 5, and the web or body portions 6, of one section, is usually turned over so as to produce the flange parallel with the ribs as indicated by 11, Figs. 3 to 6, at the opposite ends of the section; while another section is provided with a recurved portion 12, at its opposite ends, each producing a pocket for the reception of a flange 11 of the complementary section. Two sections 10 of the crimped material thus produced and of the same length are then placed together, one upon the other, with the ribs 5, of the section alternating with each other and the outer edges 8 of the ribs resting against opposite 15 web or flat portions 6, of the complementary sections. This produces the rectangular or square tube-structure and effect illustrated in Fig. 4. In order to tightly lock and join the sections together, the flanges 11 at the 20 opposite ends of one section, are entered into the pocket formed by the recurved portion 12, at the opposite ends of the complementary section, this interlocking structure making a close, frictional fit very quickly 25 produced in assembling. The recurved portion is usually made close to one of the ribs which gives strength to the article at the joint. The sections, when thus joined and the flanges interlocked, as shown in Fig. 4, 30 are then firmly soldered together so as to make a permanent square-tube-section, a number of which are joined together to form the radiator, the solder 13 being the joining medium. The tube-sections thus placed together in the desired number have set 35 between them, at front and back, the strips or spacing-bars 14, which are interposed in order to separate the adjacent tube-sections and form the water-spaces or channels 15, 40 through which the water trickles and freely passes for cooling purposes. When arranged as shown, the spacing-bars and tube sections are soldered together at the front and back, as indicated by 16 so as to make a sub- 45 stantially solid surface which prevents the passage of fluid between the tube-sections at front and back and confines the water within the structure of the cooler between the sections of the honeycomb tubing so 50 that it can only flow from top to bottom of the cooler as is well known. When the tube-sections are together, the water channels 15, are in direct vertical lines so that the water 55 may enter at the top and flow through the radiator to the bottom in the quickest possible time and with the least resistance; and that the water, as it passes from tube to tube along the channels or passages 15 enters the enlarged chambers 17 between the tube-sections which communicate with the recesses 7, at the opposed sides of the ribs or partitions and thus comes into contact with a 60 greater cooling, radiating or condensing

surface of the tubing and, in fact, passes in between the two superposed walls of 65 the ribs 5 of the tubes. Thus, the radiator is capable of carrying off a maximum amount of heat, the fluid is not retarded in its flow and is quickly cooled or condensed, and it will be seen that fluid, flowing in 70 from the space in the cover 2 will pass down between the tiers of tubes and into and out of the recesses and chambers with considerable force, thus creating in the large spaces at the opposite ribs and lateral channels, a 75 miniature whirlpool, which will cause a considerable agitation of liquid in its passage from top to bottom of the structure. This agitation, obviously, is a cooling process for, and results in lowering the temperature 80 thereof and abstracting a greater volume of heat from, the radiating surface of the tubes.

Instead of using the spacing-bars, or strips at opposite ends of the tubes, the ends of the base-portions 6, between the ribs, can 85 be flared or bulged substantially in a semi-circle as indicated at 18, in Fig. 5, or the flare or bulge can be made substantially angular as at 19, Fig. 7, the result being that, when the made-up tubular sections are set 90 together, the flared portions will abut and co-operate to hold the intermediate body-portions separated so as to produce the water- 95 passage or channel 15, as in the structure of Figs. 4 and 6.

Instead of making the tube-sections from two sheet-sections, as shown in Figs. 4, 5 and 6, said tube-sections may be made from a single sheet-section, Fig. 8, with the same form of joint 11-12, as in Figs. 4, 5 and 6. 100 In Fig. 8, the tube-section is made of a single sheet-section, folded upon itself so as to produce a reinforced side portion 20 of three superposed thicknesses of material and bring the ribs 5 of the opposed portions 21 105 and 22 of the same sheet-section into alternation, as in the other forms.

In all the forms of our invention, so far described, the radiator or condenser is made up of tube-sections having the width necessary for a tier extending from side to side or from top to bottom of the frame 1, irrespective of the size of the latter, and this whether the tube-sections be formed from one or two sheet-sections, but, it should be 110 distinctly understood that our invention is not restricted to this idea of means, because we contemplate forming the structure from tube-units consisting of one, two or more tubes as desired. To illustrate this, Fig. 9 115 shows a single tube 26 made from a single sheet-section, the side reinforce 20 and side-joint 11-12 being the same as in Fig. 8. The smaller the number of tubes in a given tube-unit, the greater the facility in repairing the same; but, we desire to lay stress 120

upon the important factor of our invention just mentioned, viz., that our structure is composed of tube-units formed into one or more tubes, as desired, and that such tube-unit is formed from one or more crimped sheet-sections, these sheet-sections, tube-units and composite structure being produced in accordance with the method or process which has been generally outlined, but 10 which will be presently definitely stated.

In all the forms of our invention, the solid or web portions 10 are arranged at opposite ends of the tube-sections, which give strength and solidity to the outer surfaces; and if 15 such solid portions occur, as they do in a five-inch long tube, at points intermediate the ends, they add stability to the partitions or walls of the tubes, it being understood that these web-portions are primarily intended for the opposite ends of the tubes and are tightly closed, and also have the function of preventing the solder from penetrating the space between the superposed portions of the walls or ribs, and have the 25 further function of creating a back-stop,—so to speak,—to the flow of the solder within the tubes, since the shoulders 10^a, operate to hold the solder and prevent it from “running” into the tubing until it becomes “set.”

30 In all forms of our invention, as illustrated in the drawings, it will be seen that the grouping of the tube-units or tube-sections is the same and that each tube-unit or tube-section is made up of one or more strips 35 or sheets of material crimped as described and having the reinforced sides or secured together at their sides or ends by an interlocking joint, which is subsequently soldered to prevent the sections from slipping apart 40 and giving rigidity to the structure. It will also be seen that each unit or section thus made is exceedingly flexible and can be handled, bent and manipulated without any danger of the sections becoming dis- 45 jointed or disturbing the form of the tubes, the tube-sections, in fact, being elastic or resili- 50 ent, since the ribs of the respective crimped sections can slide relatively to each other when the tube-sections are flexed or bent. This makes a peculiarly strong and durable construction, since jars and constant jolting of the car can, in no manner, disturb or fracture the walls of the tubing.

In the several forms of our inventions it 55 will also be observed that the same method is carried out in producing the crimped or ribbed-sections and the units or tube-sections, viz., first forming a sheet of crimped material; second, cutting the sheet of 60 crimped material into sections of predetermined lengths; third superposing one portion or section of the crimped material upon another portion or section of the crimped

material with the crimps or ribs of the respective sections spaced apart or alternating 65 with each other and the sides interlocking or reinforced; fourth, soldering or securing the interlocked or reinforced sides of the sections of crimped material, these several steps producing a tube-unit or tube-section. 70 The further additional steps produce the honeycomb structure and complete the radiator, the same being: fifth, setting in juxtaposition a plurality of tube-units or tube-sections; and, sixth, soldering or securing 75 the ends of the tubes together so as to produce a compact and solid structure.

From the foregoing description, it will be seen that we first produce a sheet of crimped material, of indefinite length, having certain structural and characteristic features which are novel and which make an article of manufacture embodying one of the important features of our invention. We then produce, from the crimped material, 80 a novel tube-unit or tube-section constituting an article of manufacture embodying additional important features of our invention. And we then produce, from the units or tube-sections, a novel radiator or condenser having other important features of our invention. Upon all these articles of manufacture, viz., the blank, the tube and the radiator or condenser and the method of producing the same, we desire to lay stress, 85 because we believe ourselves to be the first to produce a radiator in the manner and according to the mode described and, in consequence, purpose claiming the same in the broadest possible manner. 90

Having thus described our invention, what we claim and desire to secure by Letters Patent is:

1. In a radiator, a unit formed of a strip of metal having plaits therein, said strip 105 being folded intermediate its ends to form a box-like structure and to bring the plaits between the side walls thereof, said plaits extending entirely across the space between said side walls to support both of the same 110 against collapse and vibration, one end of said strip being bent to form a plurality of open plaits as a terminal thereof and the open side of the terminal plait being faced toward the other end of said strip, said latter end being bent at an angle and extended into said open terminal plait to form an interlocking joint. 115

2. In a radiator, a unit formed of a strip of metal having a plurality of spaced-apart, 120 hollow plaits formed therein, said strip being folded intermediate its ends to form a hollow structure and to bring the plaits between the side walls thereof, said plaits extending entirely across the space between 125 said side walls to support both of the same

against collapse and vibration, one end of said strip being bent to form a plurality of open plaits as a terminal thereof and the open side of the terminal plait being faced toward the other end of said strip, said latter end being bent at an angle and extended into said open terminal plait.

In testimony whereof we have hereunto

signed our names in the presence of two subscribing witnesses.

GEO. DE FÈVRE.
JAMES E. WOODBRIDGE.
